SIMULATED RACING GAME APPARATUS

Keamon Kurose, Seattle, Wash.

Application April 9, 1948, Serial No. 20,065

3 Claims. (Cl. 273—86)

1

This invention relates to a race track type amusement device and an object of this invention is to provide a race track type amusement device which is chance controlled, which is highly entertaining and which can be used or played by one or more persons.

Another object is to provide a race track type amusement device which is well adapted to be made in an inexpensive form for the use of children as a toy and which can be made in a more substantial and durable form for adult use.

Another object is to provide a race track type amusement device comprising a racing table mounted for undulating movement about an upright central axis, said table having thereon a race track whereon wheel supported figures are movably disposed and said device being provided with means for imparting undulating movement to the table and with means for indicating the number of laps made by the racing figures around the track on the table.

Other objects are to provide a race track type amusement device which is simple in construction, not expensive to manufacture, and which is highly efficient in providing amusement to persons using the same.

Other objects of the invention will be apparent from the following description taken in connection with the accompanying drawings.

Figure 1 is a plan view of a race track type amusement device constructed in accordance with my invention.

Fig. 2 is an elevation of the same looking in the direction of broken line 2—2 of Fig. 1.

Fig. 3 is a sectional view of the same taken substantially on broken line 3—3 of Fig. 1.

Fig. 4 is an elevation looking in the direction of broken line 4—4 of Fig. 1.

Fig. 5 is a detached plan view of a racing table of a different shape than the racing table shown in Fig. 1.

Fig. 6 is a detached view partly in section and partly in elevation showing an adjusting device which can be used in connection with this apparatus.

Fig. 7 is a plan view of one type of racing device which can be used in connection with this amusement device.

Fig. 8 is a side elevation of the device shown in Fig. 7.

Fig. 9 is a side elevation of another type of racing device.

Fig. 10 is a view partly in plan and partly in section of the device shown in Fig. 9, taken on broken line 10—10 of Fig. 9.

2

Like reference numerals designate like parts throughout the several views.

This race track type amusement device comprises a frame 11 of a shape and size suitable to serve as a support and mounting means for the race track apparatus proper and as a platform 12a on which parts of the device operate.

The race track apparatus comprises a pan shaped racing table 12 which is supported for undulating or swash plate movement about an upright central axis. The racing table 12 has an upwardly curved marginal flange 13 which forms the outer wall of a race track 14. Another upwardly extending flange 15 forms the inner wall of the race track 14. Both of the flanges 13 and 15 curve upwardly from the track 14 and are inclined outwardly relative to the track. This provides a construction in which wheel supported racing pieces on the track 14 can run partly on these flanges and climb part way up said flanges as they race around the track.

The center of the racing table 12 is provided with an indentation 16 which fits over and rests upon the tapered upper end portion 17 of a rigid upright post 18. This post 18 thus supports the race table 12 for undulating movement about an upright centrally positioned axis. Any suitable means is provided for preventing rotation of the table 12. This can be accomplished by providing on the table 12 an outwardly protruding forked bracket 19 which fits over a fixed upright post 19a secured to the frame 11.

One satisfactory way of imparting undulating movement to the table 12 is to secure to the bottom of said table a downwardly extending preferably inclined track flange 20 which terminates in an inwardly directed tread portion 21 on which a wheel 22 is adapted to roll. The tread portion 21 is preferably formed at a proper angle so that any portion thereof which contacts the platform of the frame 11 will rest flatly against such frame. The track flange 20 is circular and is concentrically positioned relative to the bearing socket 16 on which the table 12 is supported. Preferably the table 12 is formed of a paper or fiber product and preferably the track flange 20—21 is formed of sheet metal and is readily detachable from the table 12.

The wheel 22 is rotatively mounted on a cross arm 23 which is secured to a sleeve 24 supported on the post 18. Preferably another wheel 25 is mounted on an end portion of the cross arm 23 diametrically opposite to the wheel 22. The use of the second wheel 25 is desirable to provide a better balanced structure but the device is oper-

ative without this second wheel 25. The wheel 25 is closer to the axis of the post 18 than is the wheel 22 to avoid interference with indicator mechanism hereinafter described and this wheel 25 runs on the horizontal platform 11a provided by the frame 11.

The post 18 is of substantial length and the lower end portion of said post is preferably secured to a base block or bearing member 26 which is supported by the frame 11. In this way the post 18 is rigidly supported in an upright position. The sleeve 24 is rotatively mounted on the post 18 and the lower end portion of said sleeve is fixedly secured to a bearing block 27. The two blocks 26 and 27 are spaced apart by balls 28 which cooperate with the blocks to form an anti-friction step bearing.

Suitable driving means is connected with the sleeve 24. This driving means can be manually operated or power operated. The driving means shown in the drawings comprises a sheave 29 secured to the sleeve 24 and connected by a belt 30 with another sheave 31 on an upright shaft 32 which is positioned at the side of the table 12. For manual operation a crank 33 can be secured to the shaft 32. Obviously this shaft 32 can be driven by an electric motor or by a spring motor. Also either an electric motor or a spring motor can be mounted within the housing formed by the frame 11 and connected by worm or bevel gear means with the sleeve 24.

Obviously when the sleeve 24 and cross arm 23 connected therewith are rotated the wheel 22 will be caused to move in a circle on the tread member 21 and this will impart an undulating movement to table 12. If wheeled figures are supported on the race track portion 14 of the table 12 this undulating movement will cause the figures to move progressively around the track 14 as hereinafter explained.

If it is desired to limit rotation of the shaft 32 to one direction only then a ratchet wheel 70 can be secured to this shaft and a pawl 71 positioned in engagement with this ratchet wheel, see Fig. 2.

To enable users of this game to select in advance of a race, the number of laps to be run, I provide indicator means. One preferred form of this indicator means is hereinafter disclosed but the same can be widely varied. This indicator means comprises a star wheel 34 secured to a shaft 35. The points of this star wheel 34 extend upwardly through an opening 36 in the frame platform 11a, into the path of a contactor 37 which is carried by the cross arm 23 so that the star wheel 34 will be advanced one step for each complete revolution of the cross arm 23. The outer end portion of the shaft 35 has an arm 38 secured thereto. Another star wheel 39 is secured to a shaft 40 and positioned with its points in the path of movement of the arm 38. Each time the shaft 35 makes one complete revolution the arm 38 will contact one point of the star wheel 39 and advance the same one step. The shaft 40 is rotatively mounted in a frame piece 41 and extends through a dial member 42 and has an indicator arm 43 secured thereto. A hand wheel or knob 44 is secured to the outer end of the shaft 40 so that this shaft can be turned to set the indicator arm 43 in any desired position, depending upon the number of laps selected for a race. The end of a race can be signalled by the sound of a bell 45. The bell 45 is sounded by the dropping of a lever arm 46 which is fulcrumed on a pivot 47 and has one end thereof positioned

in the path of the indicator arm 43. As the indicator arm 43, moving counterclockwise, Fig. 4, approaches its zero or starting position, which in the drawings is the position in which said indicator arm points downwardly, it will first engage and angularly move the lever arm 46 clear of the bell 45 and will then release said lever arm and allow the outer end of the same to strike and sound said bell.

The racing table can be circular in shape, as shown in Figs. 1 to 4, or it can be of a different shape such as the oval or elongated table 48 shown in Fig. 5. The elongated table 48 has an upwardly and outwardly extending marginal flange 49, which in cross section, is shaped like the flange 13 of the table 12 and functions in the same manner. Also the oval table 48 has an upwardly and inwardly extending inner flange 50 which is oval in plan and which, in cross section, is shaped like the flange 15 of the table 12 and functions in a similar manner. The under side of the oval table 48 has a circular track flange 51 secured thereto. This track flange 51 has a tread flange 52 and is of the same size and shape and is similar in every way to the track flange 20-21 of Figs. 1 to 4 so that the two race tables 48 and 12 can be used interchangeably with the mechanism shown in Figs. 1 to 4. The track flange 51 is shown by dotted lines in Fig. 5. The center of the oval table 48 has a bearing recess 53, shown by dotted lines in Fig. 5. This bearing recess 53 corresponds to the bearing recess 16 of the table 11. The portion of the oval racing table between the flanges 49 and 50 forms an oval track 54 in which racing figures can be operated.

The racing figures used on the track can be spherical figures, such as marbles, or they can be small wheel supported figures, vehicles, boats or the like. Figs. 7 and 8 show a small car 55 having two rear wheels 56 and a front ball 57 on which it runs. The ends of the car 55 are rounded and the wheels 56 and ball 57 are within the outlines of the frame so that when a number of these cars are used on the track they will not catch on each other but will be deflected away from each other if they bump together on said track. Preferably the ball 57 is of heavy material, such as a steel ball, so that the weight of this ball will tend to keep the end of the car in which the ball is supported ahead of the other end when the car is moving by gravity along the inclined race track. The ball is also free to roll sidewise and for this reason makes the car more flexible and helps to steer the car along the track. If desired the body of the car 55 can be made to simulate a boat or a bus or any other vehicle.

Figs. 9 and 10 show a frame 58 supported on a front ball 59 and rear wheels 60. The wheels 60 are secured to a shaft 61 which has a crank portion 62. A figure 63, which can be that of a horse, has its rear leg 64 pivotally supported on the crank 62 and its front leg 65 connected by pivot means 66 with the front end of the frame 58. Obviously rotation of rear wheels 60 will rotate the crank shaft 61-62 and this will move the horse 63 to simulate a gallop or run.

Preferably the vehicles, figures and the like used on the track are distinctively colored to differentiate them one from another.

It may be desired to vary the pitch or slope of the tables 12 and 48. One way of doing this is to provide a conical extension member 67, Fig. 6, which can be fitted over the top end of the post 18 and used as a pivotal support for the racing

table. This spaces the center of the racing table farther away from the frame 11 and results in an increased slope of pitch.

Preferably the race track portion of each table 13 and 48 has perforations 69 into which pins 68 or other deflector devices can be plugged. These deflector members 68 offer obstruction to the figures on the track and deflect and change the course of these figures and cause the figures to vary their speed and serve to make the races more interesting.

In the use of this racing device a desired number of the figures to be used are placed on the track with the race table 12 or 43 at rest and preferably with the lowermost part of this table positioned alongside of the indicating mechanism. In this connection it will be noted that Figs. 2, 3 and 4 show the table tilted so that the portion of the table farthest away from the indicating mechanism is at the lowest elevation. Before the start of a race the players decide on the number of laps to be run and set the indicator arm 43 in a position relative to the dial 42 to indicate this number of laps. For instance, if they set the indicator arm 43 in line with the hole in the dial which is marked 15 then the cross arm 23 will have to make fifteen revolutions to angularly move this indicator arm 43 counterclockwise, Fig. 4, far enough to ring the bell 45.

After the indicator arm 43 has been set a player rotates the cross arm 23 in the direction indicated by the arrow in Fig. 1 by turning the crank 23. As the cross arm 23 rotates the wheel 22 rolls around on the tread member 21 of the track flange 20 and imparts an undulating movement to the race table 12 about the axis of the post 18 which causes the figures on the table to run around the track. The speed of movement of the figures can be varied by varying the speed of undulation of the table. As these figures move around the track they will also move in and out of said track and will be deflected from straight paths by the pins or like deflector members 68 which are placed in the holes 69 in the track and said figures will crowd the flanges 13 and 15 or 49 and 50 and will tend to run up on these flanges, particularly the marginal flanges 13 and 50. Due to this irregularity of movement the figures in the race will lose and gain relative to each other and will pass each other and it will not be possible to tell in advance which figure will be in the lead when the finish bell rings.

The foregoing description and accompanying drawings disclose a preferred embodiment of my invention but it will be understood that this disclosure is merely illustrative and that changes can be made within the scope and spirit of the following claims.

I claim:

1. An amusement device comprising a racing table having thereon an endless curved race track adapted to receive racing figures which run on the track; means supporting said racing table for undulating movement about an upright central axis; means restraining said racing table against rotary movement; a circular track flange rigid with said table and extending downwardly therefrom and having an inwardly directed annular tread portion; a wheel positioned on the tread portion of said track flange; and means for moving said wheel in a circular path around said

tread portion to impart undulating movement to said racing table.

2. An amusement device comprising a racing table having thereon an endless curved race track adapted to receive racing figures which run on the track; means supporting said racing table for undulating movement about an upright central axis; means restraining said table against rotary movement; platform means underneath said table; a circular track flange secured to the under side of said table and having an inwardly directed tread portion spaced from the table and adapted to engage with the platform so that the point of contact of said track flange with said platform will move around the platform as the racing table undulates; a cross arm supported for rotative movement above the platform; means for rotating said cross arm; and a wheel on said cross arm positioned on said tread portion of said track flange and movable in a circular path on said tread portion to impart undulating movement to said table.
3. An amusement device comprising a racing table having thereon an endless curved race track adapted to receive racing figures which run on the track; a centrally positioned rotatively mounted upright post supporting said racing table for undulating movement about an upright central axis; means restraining said table against rotary movement; platform means underneath said table; a circular track flange secured to the under side of said table and having an inwardly directed tread portion spaced from the table and adapted to engage with the platform; a cross arm carried by said post and supported for rotative movement above the platform; means for rotating said post and said cross arm; a wheel on said cross arm movable in a circular path by rotative movement of said cross arm and adapted to run on said tread portion of said track flange to impart undulating movement to said table; and another wheel on said cross arm positioned diametrically opposite and at a lesser radial distance from said post than said first mentioned wheel and adapted to run on said platform to counterbalance the lift exerted by said circular track flange on said first mentioned wheel.
